UNITED STATES PATENT OFFICE.

JOHN ROGERS, OF MADISON, WISCONSIN, ASSIGNOR TO NATIONAL CONCRETE MACHINERY CO., OF MADISON, WISCONSIN, A CORPORATION OF WISCONSIN.

REINFORCEMENT FOR CONCRETE FENCE-POSTS.

1,126,570.

Specification of Letters Patent. Patented Jan. 26, 1915.

Application filed October 22, 1912. Serial No. 727,199.

To all whom it may concern:

Be it known that I, JOHN ROGERS, a citizen of the United States, residing at Madison, in the county of Dane and State of Wisconsin, have invented a new and useful Reinforcement for Concrete Fence-Posts, of which the following is a specification.

This invention has reference to improvements in reinforcements for concrete structures, especially fence posts, but capable of use in other connections, and the object of the invention is to provide a reinforcing unit capable of being quickly placed in the desired form to constitute a column-like reinforcement for posts and other like structures, but which may be initially in a spread out condition whereby many reinforcements may be bundled together very compactly to be formed when needed into the desired shape with little or no aid from tools.

In accordance with the present invention each unit comprises an appropriate number of rods designed to extend longitudinally of the structure to be made where such structure is columnar, as in the case of a fence post, and these rods are connected and spaced by joining members which may be in the form of wires preferably of smaller gage than the longitudinal member, and these wires are so formed at intervals as to partially embrace the longitudinal rods to an extent to hold them against accidental displacement, while one end of each connecting wire or strand is sufficiently prolonged and bent at the free end into a locking loop to engage the remoter terminal one of the series of longitudinal wires, bars or rods in a manner to hold these longitudinal rods in a columnar group.

The invention will be best understood from a consideration of the following detailed description taken in connection with the accompanying drawings forming a part of this specification, with the further understanding that while the drawings show a practical form of the invention, it is by no means limited to any strict conformity with the showing of the drawings, but may be changed and modified so long as such changes and modifications mark no material departure from the salient features of the invention.

In the drawings:—Figure 1 is an elevation of a reinforcement unit spread out in position for shipment. Fig. 2 is a perspec-

tive view of a unit assembled in columnar form as it is used in a post or other column-like structure of concrete. Fig. 3 is a longitudinal vertical section of a completed post with the reinforcement embodied therein. Fig. 4 is a perspective view of the post of Fig. 3, but drawn to a different scale. Fig. 5 is a section on the line 5—5 of Fig. 3 but drawn to a larger scale.

Referring to the drawings there is shown a reinforcement composed of longitudinal rods, strands or wires 1 and transverse wires or connecting strands 2, the number of each type of strands depending upon the size and character of the structure to be reinforced. Usually the longitudinal rods 1 are of larger gage than the transverse connecting strands or wires 2, but not necessarily so. Where the column to be reinforced is of constant diameter the strands 1 may be in parallel relation one to the other, but where the column tapers then the strands 1 will approach toward one end of the structure and the connecting wires or strands 2 will correspondingly shorten toward that end of the rods or strands 1 agreeable to the smaller end of the column. The longitudinal rods 1 are preferably, though not necessarily, crimped or corrugated to a slight extent to prevent any tendency toward longitudinal movement. The connecting wires 2 are formed at appropriate intervals with partly closed loops 3, each of a size to incompletely embrace a corresponding rod 1 to an extent that the open mouth of the loop is less in diameter than that of the rod, and these loops are spaced apart in accordance with the desired spacing of the rods 1 at the points where the connecting wires 2 are placed. It is customary to provide connecting wires 2 near the ends of the group of rods 1 and at one or more intermediate points in accordance with the length of the column and reinforcing rods 1. The wires 2 are sufficiently pliable to permit the laying out of the unit made up of the rods 1 and wires 2 in a substantially flat condition, but without spreading the loops 3 sufficiently to permit the escape of any of the rods 1, and it is customary to manufacture the units in such form so that many units may be piled one on the other and bound together in any appropriate manner for shipment, thus occupying but a comparatively small space, and even a materially less space than would be the case were the rein-

forcements assembled in columnar form and nested. One end 4 of each wire 2 is continued beyond the rod 1 near such end of the wire and this continuation is equal to the spacing between the rods 1 plus a loop 3 and sufficient additional wire to constitute a manipulating member indicated at 5. The extension 4 permits the formation of the unit into a closed column, as indicated in Fig. 2, 10 with the mouths of the loops all toward the longitudinal center line of the column, with the loops 3 adjacent to the manipulating member 5 in embracing relation to that rod 1 remote from the extension 4, and by an appropriate formation of the loop 3 at the outer end of each extension 4 this loop may 15 be made to snap over the appropriate terminal rod 1 sufficiently to hold the columnar form after the reinforcement has been embedded in the concrete structure. The terminal or latch loop 3, designed to lock on the longitudinal rod 1 at the other end of the series, will give sufficiently to snap over such rod, because the mouth of the loop is 20 not so nearly closed as in the other loops when the reinforcement is bent into a closed column form. However, the terminal portions of the wires 2 may have their loops bent into more firm embracing relation with 25 the corresponding rods 1 by the use of an appropriate tool after the unit has been formed into the column shape. The corrugated or crimped form of the rods 1 serves to hold the wires 2 in the position at which they have 30 been initially placed.

The reinforcement unit is of a character which permits its ready manufacture by an appropriate machine, an example of which is disclosed in my copending application, 40 Serial No. 815,462, filed January 30, 1914, wherein the rods may be fed at proper intervals for spacing and the wires 2 may be drawn into the machine and bent or looped about the rods 1 at suitable spaced points 45 both with respect to the rods and the wires without the necessity of wrapping the wires about the rods, but only bending the wires about the rods to an extent sufficient to cause portions of these wires to approach closer 50 than the diameters of the rods. By this means the units are made up of both longitudinal and transverse members effectively anchored together with the proper spacing of the parts and in a condition best adapted 55 for shipment while the transverse wires yield sufficiently to permit the folding together of the unit to such an extent that the unit will assume a columnar form with those portions constituting the long edges of the 60 unit united firmly and unyieldingly.

It is a matter of importance that the longitudinal rods 1 should be held firmly in spaced relation while in the mold, in view 65 of the method practised of manufacturing the post, which method is shown in my prior

Patent No. 811,873, dated February 6, 1906. If insecurely connected by the wires 2, the jostling or shaking of the mold would displace the rods to an extent that they would fail in their purpose of properly reinforcing the post. By the peculiar connection between the wires and the rods, the latter are maintained in proper position while the filling of the cement around the reinforcement is going on, and until the cement has 75 fully set.

The use of the unit is apparent from Figs. 3, 4 and 5. In Fig. 3 the unit is shown embedded in a concrete post 6, an exterior view of which is shown in Fig. 4. This post 80 may have produced therethrough a suitable number of passages 7 for the reception of fence wire or holding devices for fencing.

It will be observed from the showing of Figs. 3, 4 and 5 that the unit when bent into columnar form may be entirely embedded in a concrete body of appropriate composition and will render such concrete body particularly resistant to rupturing forces, while the stiffness of the reinforcement is greatly enhanced by the structure thereof, since the rods 1 are stiffened by the crimping, and the connecting wires 2 each forming a substantially closed band serve to further stiffen as well as connect the rods 1. 95

What is claimed is:

1. A reinforcement unit for columnar form concrete structures in initially flat shipping form, comprising a series of longitudinal members each of a length corresponding to the length of the columnar form concrete structure, and a series of transverse connecting members each formed with a series of substantially equi-spaced and partly closed loops having a mouth portion of less diameter than that of a longitudinal member, and each partially embracing a longitudinal member, the transverse members each having one end extended beyond the series of longitudinal members and there formed into a partly closed loop spaced from the series of longitudinal members in agreement with the spacing of the other loops and having its open mouth portion of a diameter to snap over a longitudinal member in locking engagement therewith when the reinforcement unit is bent into the column form to hold the unit in such form, the open mouths of the partly closed loops being then all presented toward the longitudinal center line of the column, whereby the bending of the unit brings such partially closed loops into tighter engagement with the longitudinal members. 115

2. A reinforcement unit for columnar form concrete structures in initially flat shipping form, comprising a series of longitudinal crimped or corrugated rods or wires, and a series of transverse connecting wires each formed into equi-spaced incomplete 120

loops partially embracing the longitudinal wires and each loop having its mouth portion of less diameter than that of a longitudinal wire, each transverse wire also being 5 provided with an extension beyond the series of longitudinal wires connected thereby and there formed into an additional partly closed loop spaced from the series of longitudinal members in agreement with the 10 spacing of the other loops and having its open mouth portion of a diameter to snap over a longitudinal wire in locking engagement therewith when the unit is bent into column form to hold the unit in such form, 15 and the mouth portions of all the loops being then directed toward the longitudinal center line of the column, whereby the bending of the unit brings said partially closed loops into tighter engagement with the longitudinal rods or wires. 20

3. A reinforcement unit for columnar form concrete structures in initially flat shipping form, comprising a series of longitudinal members, each of a length corresponding to the length of the columnar form concrete structure, and a series of transverse connecting members each formed into a series of substantially equi-spaced and partly closed loops, each having a mouth portion of less diameter than that of a longitudinal member, and each partially embracing a longitudinal member, the trans-

verse members each having one end extended beyond the series of longitudinal members and there formed into a partly closed 35 loop spaced from the series of longitudinal members in agreement with the spacing of the other loops, and having its open mouth portion of a diameter to snap over a longitudinal member in locking engagement therewith when the reinforcement unit is bent into the column form to hold the unit in such form, the open mouths of the partly closed loops being then all presented toward the longitudinal center line of the column, 40 whereby the bending of the unit brings said partially closed loops into tighter engagement with the longitudinal rods or wires, each connecting wire beyond the additional loop having an extension constituting a manipulating member and representing a portion 45 of that part of the connecting wire joining the reinforcement structure with the next one in order of manufacture, whereby the units may be severed without waste from a 50 continuously manufactured web.

In testimony, that I claim the foregoing as my own, I have hereto affixed my signature in the presence of two witnesses.
